United States Patent Office

Des. 227,164
Patented June 5, 1973

227,164

PAIR OF SPECTACLES

Anthony Shindler, Brookline, Mass., assignor to American Optical Corporation, Southbridge, Mass.

Filed Mar. 16, 1971, Ser. No. 125,004

Term of patent 14 years

Int. Cl. D16—06

U.S. Cl. D57—1 F

FIG. 1

FIG. 2

FIG. 3

FIG. 1 is a front elevational view of a pair of spectacles embodying my new design;

FIG. 2 is a top plan view thereof, the temples being broken away for convenience of illustration; and

FIG. 3 is a side elevational view thereof the opposite side being identical.

I claim:

The ornamental design for a pair of spectacles, as shown and described.
